UNITED STATES PATENT OFFICE.

JOHN D. WARREN, OF BURLINGTON, IOWA.

DESIGN FOR A SHOW-CASE COUNTER.

SPECIFICATION forming part of Design No. 22,963, dated December 12, 1893.

Application filed August 11, 1893. Serial No. 482,945. Term of patent 7 years.

To all whom it may concern:

Be it known that I, JOHN D. WARREN, a citizen of the United States, residing at Burlington, in the county of Des Moines and State of Iowa, have invented and produced a new and original Design for a Show-Case Counter, of which the following is a specification, reference being had to the accompanying drawing, showing a part thereof.

10 The subject of my design is a counter and show-case, having front and top panels, substantially as hereinafter described.

In the accompanying drawing, which is a

perspective view of my design for a counter and show-case: A represents the body thereof, B a base plinth, C the top cornice, D, D', D'' doors, exposing the interior.

S represents the show-case top panel, and S' the front panels.

I claim as my invention—
The design for a show-case-counter, substantially as herein shown and described.

JOHN D. WARREN.
